UNITED STATES PATENT OFFICE.

HENRY T. PERRAM, OF STAMFORD, ONTARIO, CANADA.

THILL-CO尤LING.

SPECIFICATION forming part of Letters Patent No. 251,985, dated January 3, 1882.

Application filed August 20, 1881. (No model.)

To all whom it may concern:

Be it known that I, HENRY TOPHAM PERRAM, of the village of Stamford, in the county of Welland, in the Province of Ontario, Canada, farmer, have invented a certain new and useful Thill-Coupling, of which the following is a specification.

The object of the invention is to provide a coupling which can be quickly connected and easily disconnected, but which will not readily become unfastened by itself.

In the drawings, Figure 1 is a perspective view, showing the coupling complete. Fig. 2 is a cross-section of the same. Fig. 3 is a perspective detail, showing the coupling with the shaft removed. Fig. 4 is a detail of the coupling-pin and ends thereof. Fig. 5 is a detail of the spring used in fastening the coupling.

In the drawings, A is the ordinary socket to receive the end of the thill B.

C is a pin, having fastened on one of its ends a head, D, having a curved slot, a, made in it to receive the spring E when in position, as shown in Fig. 1.

F is a hook-shaped detachable bracket, formed to gripe one of the lugs of the bracket A, and having a hole, b, in it, through which the end of the spring E is inserted.

G is a piece of rubber or other suitable elas-

tic material inserted behind the end of the thill, 30 immediately below the center of the spring E.

In order to couple the shaft the thill is put in the socket in the ordinary way and the pin C inserted. The bracket F is then hooked onto its lug, as shown in Fig. 2, when, the rubber G being inserted, the end of the spring E is passed through the hole b and its front sprung into the slotted passage-way a on the head D of the pin C. The coupling is then complete, and it can be uncoupled by reversing the operation described.

What I claim as my invention is—

In a thill-coupling in which the end of the thill B is inserted in the usual way into the ordinary socket B, a coupling-pin, C, provided with 45 a head, D, having a slotted groove, a, in combination with a detachable hook-bracket, F, and spring E, one end of the latter fitting into a hole, b, in the detachable bracket F, and its other end slipped into the slotted passage-way 50 a in the head D, the center of the spring being sprung over an elastic block, G, substantially as and for the purpose specified.

H. Y. T. PERRAM.
